poration of Ohio

Application June 9, 1955, Serial No. 514,302

2 Claims. (Cl. 239—132)

The present invention relates to blower-type cleaning apparatus, and particularly to improvements in soot blowers of the type intended for installation in high temperature zones of furnaces and the like.

An important object of the invention is to provide an improved soot blower equipped with cooling means constructed and arranged in such manner that the blower nozzle and adjacent parts may be installed in high temperature zones, as, for example, in the water walls of large industrial boilers, and will endure for long periods of time when so installed without the necessity for retracting the nozzle during intervals when blowing medium is not flowing therethrough.

A related object is to provide such a construction which is of simple and inexpensive character, which is compact and light in weight, which involves no special or complicated moving parts, which is not apt to become clogged, which has a long life, and which requires a minimum of attention and servicing.

In the past it has not been found practical to construct the blower tubes and nozzles of soot blowers intended for such high temperature installations of a material which is capable of withstanding the heat during the periods when the unit is not being cooled by the projection of the blowing medium therethrough, and it has accordingly become universal practice to employ retractable soot blowers in such installations. Previous efforts to utilize a cooling medium such as air have not been successful for several reasons, among which may be mentioned the high radiant heat impingement, and the difficulty involved in the provision of a shielding screen of cooling air. In accordance with the present invention the exposed portion of the nozzle is covered by a stainless steel shroud which is spaced from the blower tube. Cooling air is caused to flow through the shroud, between the shroud and the blower tube and outwardly into the boiler through an opening which substantially surrounds the nozzle. A substantial proportion of the radiant energy is reflected by the stainless steel shroud, while the remaining extraction of heat is effected by the cooling air.

Other objects and advantages of the invention will become apparent upon consideration of the present disclosure in its entirety.

In the drawing:

Figure 1 is a vertical sectional elevational view through a portion of a furnace wall, showing a soot blower constructed and installed in accordance with our invention;

Fig. 2 is a longitudinal central sectional view, on a larger scale, of the blower nozzle assembly;

Figs. 3 and 4 are cross-sectional views taken substantially on the lines 3—3 and 4—4 respectively of Fig. 2; and

Fig. 5 is a horizontal sectional plan view taken substantially on the line 5—5 of Fig. 1, and looking in the direction of the arrows.

Referring now to the drawing, reference character 10 designates the wall of a boiler setting, the details of

2

which are not illustrated, since they form no part of our present invention, although a water wall section is illustrated, as typifying a high temperature region for which our invention is suitable. Water wall tubes as 12 extend vertically inside the wall, which is also provided with an internal pocket in the area of the opening 14 for the blower assembly, the pocket being lined by a metal support plate 15 covered on the inside of the furnace by refractory cement as 16. The supporting plate carries on its outer surface a mounting plate 18 to which a sleeve 20 is bolted or otherwise attached in a position concentrically surrounding and projecting outwardly from the blower tube opening 19 in the plates 15, 18. The water wall tubes in line with the opening 19 are bent laterally to provide clearance for the blower, as shown in Figs. 1 and 5. The construction and arrangement of these parts are essentially conventional and will require no detailed description. The blower driving unit is illustrated in outline only, and is generally designated 22. The details of construction of the blower driving head are also subject to variation and form in themselves no part of our present invention.

The driving head is equipped with a driving motor 24 which when the blower is in operation is arranged to 25 rotate the nozzle tube 30. The driving head is of the type wherein the blowing fluid is delivered through the head, to which the fluid is supplied through a suitable supply tube 26, the delivery of the blowing medium from the head being controlled by a valve (not shown) contained in the head and which is operated by and in response to rotation of the driving mechanism. When the valve is open, the blowing medium is conducted from the head through a tube 28. The tube 28 is drivable by the head, and carries rigidly secured thereto the nozzle block 35 tube 30, which, as shown at 32, may be terminally welded to the tube 28 to form a coaxial extension thereof.

The end of the nozzle block tube 30 projects into the furnace and is closed except for the discharge opening 33 defined by the nozzle ring 34, which is welded as at 40 35 in a suitable opening in the block tube. The nozzle block tube carries upon its exposed end a caplike shroud member 36, larger in all dimensions than the block tube, so that its walls are spaced outwardly from those of the block tube, the shroud extending entirely around the 45 side and end walls of the block tube which would otherwise be directly exposed to the heat within the furnace, except for the small area represented by the opening 38 which is formed in the shroud in a position substantially concentric with the nozzle member 34. The opening 38 is somewhat larger than the nozzle member 34, to permit 50 air to be discharged from the shroud between the shroud and nozzle ring, as well as to permit the discharge of the blowing medium. The rear portion 40 of the shroud is substantially cylindrical and is open, being held in concentrically out-spaced relation with respect to the block tube 30 by suitable peripherally spaced welded lug portions 42.

A cooling air supply tube 44 extends over the rear extremity 40 of the shroud 36, the shroud being rotatable 60 with the block tube in the outer end of the tube 44. Tube 44 extends rearwardly over the block tube 30 and feed tube 28 to a manifold 45 which encircles the feed tube 28 at a position between the driving head and the furnace wall. The interior of the tube 44, which is substantially larger in diameter than the tubes 28 and 30, communicates with the interior of the manifold 45 which is in turn in communication with a cooling air supply pipe 46. The spaced concentric positioning of the tubes 28, 30, 65 44 is also maintained by spacing lugs 48 which are secured to the tube 28 as by welding and rotate within the tube 70 44.

The shroud 36 is formed of relatively light gauge stainless steel and it is only secured in the area of the three locating lugs 42. The shroud is thus free to flex under heat-induced stresses. The highly reflective surface of the stainless steel also reflects a substantial proportion of the radiant energy impinging thereon, reducing heat transmission to the block tube 30, which may be formed of ordinary mild steel. The heat transmission is also reduced by cooling air supplied through the pipe 46, manifold 45 and conduit 44 to the interior of the shroud. The air is guided over the entire interior of the shroud before being discharged through the opening 38.

The cooling air supply may be derived from the air employed to create pressure within the boiler, where the boiler is of the now commonly used positive pressure type, and the air flow is maintained throughout the entire time when the blower is not operating. This cooling air for the blower constitutes one of the means for pressurizing the interior of the furnace. It will be observed that the only area where radiant heat can impinge upon the block tube 30 and nozzle ring 34, is directly beneath the opening 38, and that in this area the concentration of cooling air is the greatest, so that the wiping effect of the air upon these regions is greater than in the other areas inside the shroud and is effective to sufficiently cool these parts despite the impingement of radiant heat thereupon through the opening.

The stainless steel from which the shroud is formed has a highly reflective outer surface and may be so thin as to be easily distortable due to heat induced stresses, as indicated, and would not be stiff enough to support itself and to serve as the nozzle block. Thus it imposes very little weight load on the nozzle block and does not substantially increase the bearing loads or the tendency of the block to sag.

While it will be apparent that the preferred embodiment of the invention herein described is well calculated to fulfill the objects and advantages first above stated, it will be appreciated that the invention is susceptible to variation, modification and change without departing from the fair meaning and proper scope of the appended claims.

We claim:

1. In a soot blower construction, in combination with a relatively rigid blower tube having a cantilever outer end portion from which blowing medium is adapted to be discharged into a high heat zone and having a nozzle orifice portion in said end portion for discharging the

blowing medium, a protective shroud entirely supported and carried by, and spacedly encircling, said outer end portion of the blower tube, and having a discharge opening substantially aligned with but larger than the nozzle orifice, securing means engaging the tube and the shroud at spaced localized areas and forming the entire support for the shroud and securing the shroud to the tube in surrounding but outspaced relation thereto, the shroud being formed of relatively thin gauge, flexible, reflective metal, and having an open rear end, substantially unobstructed cooling fluid passage space being left from the open rear end of the shroud to said discharge opening between said tube and shroud and past said securing means, and supply means operatively interconnected with said open rear end of the shroud for supplying a cooling fluid to the interior of the shroud outside the tube for discharge through said shroud and outwardly through said opening in the region of said orifice, whereby the shroud reflects heat which would otherwise impinge upon said blower tube and serves to conduct cooling fluid supplied by said supply means along and in contact with both the shroud and the nozzle tube, and whereby the shroud may move with the blower tube, during any movement of the latter, due to being carried thereby, and may distort independently of the blower tube in the areas between said securing means.

2. A construction as defined in claim 1 wherein said blower tube and shroud have substantially cylindrical spaced side walls and substantially closed spaced outer ends, the shroud having an open rear end which is substantially concentric with the tube, but being otherwise substantially impervious except in the area of said opening, said blower tube being rotatable, and supply means comprising a non-rotatable feed tube interfitted with the open rear end of said shroud and extending rearwardly spacedly around said blower tube.
